ATOMIZER TOP

Theodore Bergeron, South Attleboro, Mass., assignor to
T. J. Holmes Co., Inc., a corporation of Massachusetts

Filed Aug. 23, 1962, Ser. No. 71,425

Term of patent 7 years

(Cl. D58—26)

FIG. 1 is a perspective view of an atomizer top showing my new design;

FIG. 2 is a side elevation thereof;

FIG. 3 is a rear elevation thereof; and

FIG. 4 is a top plan view thereof.

The portions shown in broken lines are for illustrative purposes only.

I claim:

The ornamental design for an atomizer top, as shown and described.
